CONTAINER WITH CLOSURE LOCKING BAND

Filed Oct. 4, 1941

FIG. 1.

FIG. 2.

UNITED STATES PATENT OFFICE

2,327,456

CONTAINER WITH CLOSURE LOCKING BAND

William F. Punte, Syracuse, N. Y., assignor to
 Continental Can Company, Inc., New York,
 N. Y., a corporation of New York

Application October 4, 1941, Serial No. 413,674

3 Claims. (Cl. 226—61)

The present invention relates to new and useful improvements in containers, and more particularly to improvements in a sheet metal container having a locking or sealing band to maintain the cover in position on the container.

In various types of containers, a cover is fitted on the body portion and maintained in position by a sealing or locking band in the form of a ring member which is adapted to engage the body portion and the cover. While these containers may be of various sizes depending upon the material to be shipped or stored, the present invention is illustrated in connection with a relatively small sheet metal container which may be of the type commonly employed for holding sardines or the like. Thus, a cover is fitted over the open end of the body portion and a suitable sealing material is employed for establishing a hermetic seal. The cover is maintained in position by a substantially U-shaped locking band which engages the cover and an outwardly projecting part of the body portion. The ends of the locking bands are connected and are maintained in locking position.

An object of the present invention is to provide a container of the above type wherein the cover is secured to the body portion by a sealing band having the ends thereof constructed and arranged to provide an easily assembled locking connection which may be easily released to permit removal of the cover from the container.

A further object of the invention is to provide a container of the above type wherein one end of the sealing band is provided with a recess within which a projection at the opposite end of the sealing band is adapted to fit for providing a locking connection, and wherein one end of the sealing band is extended beyond the locking connection so as to provide a tab portion which may be pulled outwardly to release the locking connection between the ends of the band.

A still further object of the invention is to provide a container of the above type wherein holding lugs adjacent one end of the sealing band are adapted to engage the tab portion to prevent accidental outward movement thereof and to thus maintain the locking connection between the ends of the band, the holding lugs being releasable upon outward movement of the tab portion to permit release of the locking connection between the ends of the band and subsequent removal of the cover.

The above and other objects of the invention will in part be obvious and will be hereinafter more fully pointed out.

In the accompanying drawing:

Figure 1 is a top plan view, partly in section, showing the assembled container.

Figure 2 is an enlarged end view of the assembled container, partly in section, showing the manner in which the cover is held on the container and also the locking connection between the ends of the sealing band.

Figure 3 is a fragmentary sectional view taken substantially along the line 3—3 of Figure 2, and showing the locking connection between the ends of the sealing band.

Figure 4 is an enlarged fragmentary sectional view showing a modified form of container.

Figure 5 is an enlarged fragmentary sectional view showing a further modified form of container and sealing band.

Referring more in detail to the accompanying drawing, and particularly to Figures 1, 2 and 3, the body portion of the container is illustrated as being substantially rectangular in shape and relatively shallow in depth although it is to be clearly understood that the container may be formed in any desired shape. The body portion includes a bottom wall 10 and an upstanding peripheral body wall 11. The free peripheral edge of the body wall 11 is turned outwardly and downwardly upon itself, as at 12, and then outwardly, downwardly and inwardly to provide a peripheral bead 13 which terminates in an inwardly directed horizontal shoulder 14.

The cover 15 includes a central depressed portion 16 having an upwardly extending vertical wall portion 17 disposed within the inner surface of the body wall 11. The vertical wall 17 is directed outwardly to provide a horizontal portion 18 and this portion 18 is then directed downwardly, as at 19. The free end 20 of the depending portion 19 is folded upon itself to strengthen the cover. The vertical wall portions 17, 19 and the horizontal portion 18 provide a downwardly open channel within which a suitable sealing material 21 is disposed. The outwardly turned end 12 of the body wall 11 is imbedded in the sealing material 21 so that the container can be hermetically sealed.

In order to further maintain the cover in position on the can, there is provided a sealing or locking band 22 which is substantially U-shaped in transverse cross section and thus includes upper and lower horizontal skirt portions or flanges 23, 24, respectively. When the sealing band is in sealing position, the flange portion 23 engages the outer surface of the horizontal portion 18 of the cover and the flange portion 24

engages the outer surface of the shoulder 14 on the body portion of the container. The body of the sealing band thus overlies and encloses the bead 13 and the depending outer wall 19 on the cover.

In order to lock the sealing band in position on the container, the ends of the band are provided with interlocking connections and reference is made particularly to Figures 2 and 3. The end 22a of the band 22 overlies the adjacent end 22b of the band, as shown in Figure 3. The end 22a is provided with an outward projection 25 which forms an internal recess within which an outward projection 26 on the end 22b is adapted to fit or a snap fit may be provided. The skirt or flange portions 23, 24 of the sealing band terminate and abut substantially at the line 27 and the end portion 22a is directed outwardly adjacent the opposite end 22b of the band. The end 22a is extended beyond the recessed portion 25 to provide a tab portion 28 which is adapted to normally lie next to the adjacent surface of the band.

The tab portion 28 may be provided with a knurled finger gripping surface 23a to facilitate manipulation thereof. The tab portion 28 is connected to the end portion 22a of the band by an integral connection 29 which is reduced in width so as to provide upper and lower recessed portions 30, 30a, respectively. The inner end 22b of the band is provided with upper and lower holding lugs 31, 31a, respectively, which are directed toward one another and which engage the connecting portion 29 at the recessed portions 30, 30a, respectively. In this manner, the extended connecting portion 29 of the end 22a is maintained against the inner end portion 22b of the band so as to prevent the locking connection between the recess portion 25 and the projection 26 from being accidentally released.

When it is desired to remove the band so as to open the container, the tab portion 28a is pulled outwardly and continued movement thereof will force the holding lugs 31, 31a outwardly in order to permit release of the locking connection between the recessed portion 25 and the projection 26. The band 22 can then be removed so as to permit removal of the cover 15 from the container.

In the modified form of the invention shown in Figure 4, the body wall 11a of the container is turned outwardly and is then directed downwardly to provide a depending skirt portion 32 which has the end thereof turned outwardly and folded upon itself to provide a relatively stiff shoulder portion 33 with which the bottom flange 34 on the sealing band 35 is adapted to engage. The upper flange 36 on the sealing band 35 is adapted to engage the horizontal portion 18a on the cover 15a. As described in connection with Figures 1, 2 and 3, a sealing material 21a is disposed within the channel formed by the peripheral edge of the cover and the upper end of the body wall 11a is adapted to be imbedded therein so as to seal the container. In Figure 5 of the drawing, the body wall 11b of the container is provided with an outwardly directed rib portion 37 which forms a lower horizontal shoulder 38 with which the flange 36a on the sealing band 35a is adapted to engage. The upper flange 36a on the sealing band 35a is adapted to engage the horizontal portion 18b of the cover 15b. The body wall 11b is continued above the outward rib 37 and is provided with an inwardly turned bead 39 which is adapted to cooperate with the sealing

material 21b to provide an effective seal for the contents of the container.

From the foregoing description, it will be seen that the present invention provides a highly efficient container wherein the cover is secured thereto by a sealing band. The ends of the sealing band are constructed and arranged so that they may be easily locked in position for closing the container. As illustrated, one end of the band 10 has a recess within which a projection on the opposite end of the band is adapted to fit and this locking connection may be in the form of a snap connection, if desired. One end of the band has a pull tab which extends peripherally beyond the 15 locking connection and may be pulled outwardly so as to release the locking connection. In order to more effectively maintain the ends of the band in locked position, holding lugs engage the pull tab for maintaining the locking connection 20 in position.

It is to be clearly understood that minor changes in the details of construction and arrangement of parts may be made without departing from the scope of the invention as set forth 25 in the appended claims.

I claim:

1. A container comprising a body portion having a shoulder disposed below the open end thereof, a cover for closing the open end of the body portion, a sealing band having flanges engaging over the cover and beneath the shoulder for securing the cover to the body portion, the ends of said sealing band being in overlapped relation, the outer lapping end of said sealing band having the metal therein pressed outwardly to form a recess the side walls of which are substantially at right angles to the face of the band, the inner lapping portion of the band having the metal therein pressed outwardly to form a projection fitting within said recess and preventing lateral movement of the ends of the bands relative to each other, and means for holding the lapped ends in contact with each other with the projection within the recess.
2. A container comprising a body portion having a shoulder disposed below the open end thereof, a cover for closing the open end of the body portion, a sealing band having flanges engaging over the cover and beneath the shoulder for securing the cover to the body portion, the ends of said sealing band being in overlapped relation, the outer lapping end of said sealing band having the metal therein pressed outwardly to form a recess the side walls of which are substantially at right angles to the face of the band and the inner lapping portion of the band having the metal therein pressed outwardly to form a projection fitting within said recess and preventing lateral movement of the ends of the bands relative to each other, said outer lapping end having a projecting finger piece and said inner lapping end having lugs adapted to be bent into contact with the outer face of the finger piece for holding said projection in said recess.
3. A container comprising a body portion having a shoulder disposed below the open end thereof, a cover for closing the open end of the body portion, a sealing band having flanges engaging over the cover and beneath the shoulder for securing the cover to the body portion, the ends of said sealing band being in overlapped relation, the outer lapping end of said sealing band having the metal therein pressed outwardly to form a recess the side walls of which are substantially 75 at right angles to the face of the band and the

inner lapping portion of the band having the metal therein pressed outwardly to form a projection fitting within said recess and preventing lateral movement of the ends of the bands relative to each other, the said outer lapping end having a projecting finger piece provided with a reduced neck portion between the recess therein

and the end of the finger piece, said inner lapping end having lugs struck up therefrom for engagement between which said neck portion of the outer lapping end is adapted to be placed, said lugs being bent down over the neck portion for retaining the projection in said recess.

WILLIAM F. PUNTE.
